JOSEPH D. LACROIX, OF NEW YORK, N. Y., ASSIGNOR TO EUGENE H. DAVIS, OF NEW YORK, N. Y.

CIGAR-MACHINE.

977,806.

Specification of Letters Patent.

Patented Dec. 6, 1910.

Original application filed August 16, 1904, Serial No. 220,920. Divided and this application filed January 8, 1906. Serial No. 295,155.

To all whom it may concern:

Be it known that I, JOSEPH D. LACROIX, a citizen of the United States, residing at New York, in the county of New York and State of New York, have invented new and useful Improvements in Cigar-Machines, of which the following is a specification.

This invention relates to cigar machines, and particularly to a wrapper cutting mechanism with which a transferrer is intimately related and co-operates. It is proposed to use the wrapper cutting mechanism and transferrer with any preferred wrapper applying mechanism; and the wrapper cutting mechanism includes a wrapper cutting die, the same comprising in part a perforated plate subject to suction and constituting a wrapper transferrer. This plate with the die is capable of adjustment to any angle desired, may be raised or lowered or otherwise adjusted as desired, and raised to support a wrapper while being cut. Means are employed to swing the wrapper transferrer with the superposed wrapper thereon to bring it in co-operative relation with regard to wrapper feeding mechanism, the latter being subject to suction, but permits the wrapper to be deposited from the transferrer onto the feeder mechanism. Means is provided for cutting off suction from the entire wrapper on the transferrer when the wrapper is laid upon the wrapper feeding mechanism; and means is also employed in connection with the transferrer for gradually and entirely releasing the suction from the wrapper carried thereby. The suction applied to the wrapper while on the transferrer during the cutting and delivery of the wrapper is gradually decreased; but the means for effecting the gradual reduction of the suction only becomes fully operative when the suction is entirely cut off from the wrapper. The wrapper cutting mechanism is of a simplified construction and many advantages pertaining thereto will be more fully hereinafter set forth.

The mechanism embodying the features of the invention and which will be presently described originally formed a part of my pending application Serial No. 220,920; and only so much of the mechanism has been shown in the accompanying drawings as is

deemed necessary to a full understanding of the wrapper cutting mechanism, the aforesaid application No. 220,920 disclosing the 55 mechanism interposed between this die or wrapper cutting mechanism and the remaining part of the machine as illustrated by the said application Serial No. 220,920.

In the accompanying drawings:—Figure 60 1 is a plan view of the wrapper cutting and wrapper transferring mechanism embodying the features of the invention. Fig. 2 is a view in side elevation, partly in section, of the wrapper cutting mechanism. Fig. 3 65 is a front elevation showing more particularly the mechanism for effecting the adjustment of the wrapper cutting die. Fig. 4 is a detail view of the mechanism for adjusting the wrapper cutting rollers. 70

The wrapper cutting and transferring mechanism comprises a die 132 which is of a shape to conform to that of the wrapper, said die being supported upon a suitable platform 133 and is adapted for adjustment 75 vertically and horizontally, as shown in Fig. 3, to cause proper co-operation between it and the means for cutting a wrapper placed thereon. Coacting with the die is a wrapper transferrer 134, the same comprising a 80 hollow casing provided with a curved neck 135 which is journaled upon a hollow shaft 136 connecting through a flexible conduit 137 with a suitable suction device, not shown. The free end of the transferrer carries a flat perforated plate 138 which also conforms to the shape of the wrapper and is adapted to fit within the walls of the die. The suction on the plate 138 operates to hold the wrapper firmly thereon while being cut 90 to the proper shape to form a wrapper and also while being transferred to the feeder mechanism, presently to be described. The die is hollow, as clearly shown by Fig. 2, and the plate 138 serves as a wrapper receiving and transferring member and forms at intervals the bed or receiving plate of the die and is alternately movable into and outwardly from the latter. In other words, a portion of the die constitutes both the wrapper receiving and transferring means, because the transferrer as an entirety is connected to and forms part of the die. 95

It is of course essential that during the

cutting and transferring operation of the transferrer, suction should be maintained first upon the leaf and then upon the wrapper; and it is also essential that the suction should gradually be released so that when the transferrer is in position over the wrapper feeder the wrapper may readily be deposited thereon. The suction is gradually relieved from the wrapper as the latter is moved toward and over the wrapper feeder to permit the feeder to take the wrapper from the member or plate 138, it being obvious that if the suction in the wrapper feeder as shown by Fig. 2 is greater than in the wrapper transferrer, the wrapper will be readily drawn toward the feeder. To effect this result suitable valve mechanism 139 is provided which coacts with the suction pipe 140, as shown in Fig. 1, said valve mechanism being operated through the medium of a cam disk 141 mounted on a shaft 142, the cam being provided in its face with a groove or race which is engaged by a roller bearing 143 carried by one end of a rod 144, the other end of which is connected with the lever of the valve mechanism, as shown in Fig. 1. The conduit 137 connects with the pipe 140 through the valve mechanism 138, the latter mechanism being interposed between the said conduit and pipe. Motion is imparted to the shaft 142 by suitable means to effect the result sought. The groove or race of the cam disk 141 is so shaped that the suction is gradually decreased on the wrapper as the transferrer projects over the feeder mechanism, and when the transferrer is in operative position with respect to the latter mechanism, the suction is entirely cut off. To avoid the possibility of any residual suction in the transferrer preventing the wrapper from leaving the transferrer and assuming position on the wrapper feeder, there is provided a vent 147, which always tends, even when suction is on the transferrer, to destroy it; but as the area of the suction pipe is greater than that of the vent it will have no appreciable effect while the suction is in full force or is being diminished; but as soon as the suction is cut off entirely this vent will destroy any remaining suction and permit the wrapper to be deposited onto the feeder mechanism by the suction co-operating therewith as disclosed in my copending applications Sr. Nos. 126,739 and 220,920.

Movement is imparted to the transferrer through the medium of a link shaft 148, (Fig. 1) said shaft comprising a member 149 movably carried by a pinion 150, and a member 151 having a telescopic connection at one end with the member 149 and at its opposite end pivotally connected to a projection 152 of the transferrer shaft. Motion is imparted to the pinion 150 through a rack 153 which has a roller bearing 154 traveling

in a cam groove 155 arranged in the face of the wheel 155^a and mounted upon the shaft 142. As the rack is reciprocated in opposite directions through the action of the cam race, the shaft 148 will be overturned in opposite directions and thereby operate the transferrer in a manner that will be readily understood, or to transmit the cut wrapper from the cutting mechanism to the wrapper feeder. 75

The means for severing a leaf placed upon the die comprises in this instance a pair of conical rollers 156, it being obvious that if preferred only one may be employed, and these rollers are carried by an arm 157 mounted upon a vertical post 158. The rollers are designed to travel through an arc of a circle sufficient to traverse the die and to move out of the path of movement of the transferrer, and this motion is imparted to 80 these rollers through the medium of an arm 159 secured to the post 158 and carrying a roller bearing 160 which works in a cam groove or race 161 in the face of a cam wheel 161^a mounted on the shaft 142, the 85 cam race 161 being so timed with relation to the race 155 that the rollers will have traversed the die and returned to their normal position before the transferrer starts to lift. 95

As before stated, the die is capable of various adjustments in order to insure proper presentation to the wrapper feeding mechanism. To effect horizontal adjustment of the die and also of the transferrer, there is provided a plurality of clips 162 which bear upon the periphery of the plate 163 supporting the die, and it will be seen that by loosening the screws 164 holding the clips in position, the plate 163 may be turned to vary 100 the angle of presentation of the wrapper to the wrapper feeding mechanism, thus to insure proper application of the wrapper to the bunch. To effect vertical adjustment of the die the plate 165 carrying it is provided 105 on its under side with inclined faced lugs or surfaces 166 and 167 which are adapted to coact with similar lugs or surfaces 168 and 169 on the plate 163, and it will be seen that by moving the plate in a circle it may be 110 raised and lowered as desired. That there may be perfect coaction between the rollers 156 and the die to effect perfect cutting of the wrapper the journals of the rollers are mounted in a swinging bearing 170, jam-bolts 171 operating to hold the said bearing 115 in its adjusted position.

The shaft 136, which is tubular and held within a portion of the plate 165, and the transferrer connected to the shaft are 120 adjustable equally with the die, and as one end of the shaft is connected to a flexible conduit 137 and the opposite end of said shaft to an adjustable link shaft or connection, said adjustment may be readily made with- 125 130

out disturbing the operative relation of the shaft 136. The pipe 140 may connect with any suitable suction or exhaust mechanism.

Having thus fully described the invention, 5 what is claimed is:

1. In a cigar machine, a wrapper cutting die having a fixed position, and an overturning wrapper transferrer forming the bed for the die and movable into and outwardly 10 from the said die and provided with means movable in reverse directions through the die to dispose the transferrer within said die.
2. In a cigar machine, a wrapper cutting die having a fixed position, and an overturning wrapper transferrer coacting therewith and embodying suction means projecting through and also movable in reverse directions through the die and operating to accurately position the transferrer within the die.
3. In a cigar machine, a wrapper cutting die having a fixed position, an overturning wrapper transferrer coacting therewith and having suction means connected thereto and movable in reverse directions through the die, and suction releasing means coacting with the transferrer.
4. In a cigar machine, a wrapper cutting die having a fixed position, an overturning wrapper transferrer coacting therewith and provided with a flat perforate face movable within the walls of the said die, and suction means connected to and serving as the support for the transferrer and movable into and through the die.
5. In a cigar machine, a wrapper cutting die having a fixed position, a wrapper transferrer coacting therewith and having an overturning movement alternately in opposite directions and provided with a tubular member movable through the die, suction means coöperating with the tubular member, and means for cutting off suction from the transferrer at intervals and for partially destroying the effect of suction upon the wrapper while being cut and transferred.
6. In a cigar machine, a wrapper cutting die having a fixed position, an oscillatory wrapper transferrer coacting therewith and having a portion movable therethrough, suction means combined with the transferrer for retaining a wrapper thereon, and means for cutting off suction from the transferrer at intervals, the transferrer being provided with a vent for completely destroying the effect of the suction to which the wrapper has been subjected after the suction has been cut off from the wrapper.
7. In a cigar machine, a wrapper cutting die having a fixed position, an oscillatory wrapper transferrer having a member movable into the die to form the bed of the latter and a curved hollow arm movable through the die in reverse directions, suction means 60 communicating with said arm, and means coöperating with the die for cutting a wrapper.

8. In a cigar machine, a wrapper cutting die having a fixed position, a laterally oscillatory wrapper transferrer which forms a movable bed for the die and receives the wrapper as it is cut, the said transferrer being provided with a curved tubular member movable through the die in reverse directions, suction means communicating with said tubular member, and means coöperating with the die for cutting the wrapper.

70

9. In a cigar machine, a wrapper cutting die having a fixed position, and a laterally oscillatory wrapper transferrer having a hollow casing and movable into and outwardly from the die to receive and hold the cut wrapper and a curved tubular supporting member movable in reverse directions through the die and serving as a suction means for the transferrer.

75

10. In a cigar machine, a wrapper cutting die having a fixed position, and a wrapper transferrer having a member laterally movable into and out of vertical alinement with respect to the die and which at intervals forms the wrapper receiving means within the die after the wrapper is cut, the transferrer also having a curved tubular support movable through the die and serving as a suction means for the transferrer.

80

11. In a cigar cutting machine, a wrapper cutting die having a fixed position, and a wrapper receiving and transferring means laterally movable into and out of vertical alinement with respect to the die and having a curved tubular suction member movable through the die in reverse directions.

90

12. In a cigar machine, a hollow die structure having a fixed position, and a transferring means movable into and outwardly from the die structure and laterally away from said structure and forming the wrapper receiving part of the die structure, the transferring means having suction means coöperating therewith and including a curved tubular member serving as a support for the transferring means and projecting through and movable in reverse directions through the die structure.

105

13. In a cigar machine, a fixed wrapper cutting die having a laterally swinging bed on which the wrapper is cut and serving as a transferring element for the wrapper having an overturning movement and also movable into and outwardly from the said fixed die.

110

14. In a cigar machine, the combination with a wrapper cutting die having a fixed position, of a wrapper receiving and transferring member having an overturning laterally swinging movement into and outwardly from the die and provided with suction means having a portion movable in reverse directions through the die.

125

15. In a cigar machine, the combination with a wrapper cutting die having a fixed

130

- position, a laterally swinging wrapper transerrer movable into and outwardly from the die and provided with a flat overturning member and a curved tubular arm, 5 the tubular arm projecting through the die and movable in reverse directions through the latter, and means for applying and releasing suction relatively to the said tubular arm.
- 10 16. In a cigar machine, the combination with a wrapper cutting die having a fixed position, of an overturning laterally swinging wrapper receiving and transferring member movable into and outwardly from the die.
- 15 17. In a cigar machine, a wrapper cutting die adjustable vertically and at any desired angle, a laterally oscillatory and overturning wrapper transerrer serving as a bed 20 on which the wrapper is cut and movable into and outwardly from the die, and means movable over the die and transerrer for cutting a wrapper.
- 25 18. In a cigar machine, a wrapper cutting die having a fixed position, a laterally oscillatory and overturning wrapper transerrer co-acting therewith and movable into and outwardly therefrom, and a pair of cone-shaped rollers associated in close relation 30 and automatically movable over the die at intervals and rotated by frictional contact with the latter to cut a wrapper.
- 35 19. In a cigar machine, the combination of an adjustable wrapper cutting die, an oscillatory and overturning transerrer co-acting therewith and movable into and outwardly therefrom, adjustable cone-shaped rollers rotated by frictional contact with the die to effect cutting of a wrapper, and
- mechanism for moving the rollers at intervals over the die and transerrer. 40
20. In a cigar machine, a fixed wrapper cutting die, as oscillatory and overturning wrapper transerrer movable into and outwardly from the die, and adjustable cone-shaped rollers closely associated and having mechanical means associated therewith for moving them at intervals over the die to effect cutting of the wrapper. 45
21. In a cigar machine, a wrapper cutting die having a normally fixed position with relation to an interior space, a co-operating cutting means movable over the die, mechanism for moving the cutting means at intervals over the said die, a wrapper support located at a distance from the die, and a laterally swinging wrapper transerrer having an overturning movement and movable into the die to form the cutting bed of the latter and also serving to deliver 50 a cut wrapper to the support. 55
22. The combination of a die having a fixed position around an interior space, co-operating cutting means movable over the die and having mechanism for operating the same at intervals, and a wrapper transerrer having means for laterally swinging and overturning the same alternately into the interior of the die and then into delivery position out of vertical alinement with respect 60 to and at a distance from the die. 65
